UNITED STATES PATENT OFFICE

HENRY J. SMITH, OF PHILADELPHIA, PENNSYLVANIA

JOURNAL JACK

Application filed March 16, 1925. Serial No. 15,927.

My invention is designed to provide means for relieving the load of a journal box on a wheel axle and transmitting such load to the wheel adjacent the rim thereof through a jack having means for developing the powerful force necessary for lifting the load within the narrow space available between the journal box and the wheel flange. My mechanism for accomplishing this object is, however, adapted for other uses where powerful pressure must be developed within a narrow space and particularly where the rest for the jack is offset from the center of gravity of the load.

In the preferred embodiment of my improvements, I provide a supporting foot or stanchion having scalpriform edges adapted to rest upon the flange of a wheel adjacent its web and to support wedge mechanism for moving a ram into engagement with and lifting a journal box, the wedge mechanism being operable by revoluble means located at a distance from the ram and where its operation will not be interfered with by the overhang of the journal box.

By utilizing the wheel flange as a footing for the jack, I obviate any tendency of the wheel to rise with the journal box or any necessity for providing any additional base or foundation for the jack capable of supporting the load.

The characteristic features and advantages of my improvements will more fully appear from the following description of a preferred embodiment and application of my invention, and the accompanying drawings in illustration thereof.

In the drawings, Fig. 1 is a perspective view of a preferred embodiment of my invention in position for lifting a journal box, parts being broken away; Fig. 2 is a longitudinal vertical sectional view of the jack shown in Fig. 1; Fig. 3 is a horizontal sectional view on the line 3—3 of Fig. 2; Fig. 4 is a transverse sectional view on the line 4—4 of Fig. 2; Fig. 5 is a transverse sectional view on the line 5—5 of Fig. 2; Fig. 6 is a transverse sectional view on the line 6—6 of Fig. 2; Fig. 7 is a side elevation of a stepped filler bar for insertion between the ram or

plunger and the load; Fig. 8 is an elevation of a handle by which the jack may be operated; and Fig. 9 is an elevation of a brace by which the jack may be operated.

In the form of my invention illustrated in the drawings, the casing 1 is formed with a tapering inclined hollow nose 2 at one end thereof and an enlarged chamber 3 at the other end thereof connected by the passage 4. A protuberance 5, projecting from the casing intermediate its ends, forms a supporting foot or stanchion having convex scalpriform edges 6 separated by the concavity or recess 7.

Pockets 8, formed in the upper surface of the member 5 and opening into the interior of the casing, provide seats for journalled rollers 9 which form anti-friction bearings for the wedge member 10, which has projecting therefrom the rack section 11, supported by an anti-friction roller 12, the latter being journalled in the bracket 13 fixed to the bottom of the chamber 3.

A cage 14, having a pintle 15 movable in the slot 16 of the casing, has journalled therein the rollers 17 which ride on the inclined face of the wedge 10 and support the wedge 17', having an inclined face engaging therewith.

The wedge 17' has pivotally connected therewith, by the links 18, the rack section 19 which bears against a roller 20 journalled in a bracket 21 fixed to the top of the chamber 3.

A slide or ram 22, reciprocable in the way 23 and between the anti-friction rollers 24, has in the bottom thereof sockets 25 forming seats for rollers 26 which are held in place by fasteners 27 and engage the upper surface of the wedge 17'.

A shaft 28, journalled in the casing 1, has fixed thereon a pinion 29 whose teeth engage the teeth 11' and 19' of the respective racks 11 and 19. The shaft 28 also has fixed thereto a gear wheel 30 having teeth meshing with the teeth of a pinion 31 fixed on a shaft 32 journalled in the casing 1 and having thereon a gear wheel 33 controlled by a pawl 34 operable by the handle 35.

The gear wheel 33 is rotatable by a pinion

36 meshing therewith and fixed on a shaft 37 projecting through the casing and providing angular hubs 38 for engagement with the rotor 39 of a ratchet lever 40, or in the socket 5 41 of the brace 42 having the universal joint 43.

A yoke 44 may be pivoted to the rear of the casing to support the weight of the enlarged end of the jack while it is being positioned, 10 and tongues 45 may be pivoted to the casing adjacent to the block 22 for insertion between the wheel web and journal box when the jack is being positioned.

The upper surface of the ram 22 provides 15 a seat 46 having an edge flange 47 and containing a socket for the reception of the stem of a block 22' having a seat 46' and an edge flange 47'. A stepped filler block 48 may be inserted between the seat 46 or seat 46' 20 and the journal box.

In Fig. 1 of the drawings, my improved jack is shown positioned on the flange A' of a car wheel A ready to lift the journal box B from the axle C so that the wedge D and 25 brass E may be removed. In placing the jack, the lip formed by the convex edge 6 is seated at the juncture of the wheel web and flange and being sharp bites into the flange when the load is applied so that the jack 30 cannot slip out. A tongue 45 may be inserted between the wheel web and the journal box, and the yoke 44 may rest upon the ground or a tie to temporarily hold the jack in place. The yoke 44 does not take up any of the 35 thrust or weight of the load but merely temporarily supports the end of the jack until the ram 22 makes firm engagement with the journal box.

If there is too much space between the 40 lower portion of the journal box and the seat 46 when the ram is in its lowermost position, the block 22' or a suitable step of the filler block 48 may be inserted between the parts.

45 When the jack is positioned and the pawl 34 set to prevent clockwise movement of the gear 33, the ratchet handle 40 or the brace 42 is fixed on a hub 38 and turned so as to act through the gear train to rotate the pinion 59, which advances the rack 11 to thrust the wedge 10 toward the nose 2 and retracts the rack 19 to draw the wedge 17 in the opposite direction. The movements of the wedges in 55 opposite directions elevates the block 22 and raises the journal box B, the downward thrust being transmitted directly through the foot 5 to the wheel flange and preventing the elevation thereof. As soon as the seat 46 makes bearing contact with the load, such load holds 63 the jack firmly in place, and transmission of the thrust to the wheel flange obviates any necessity for the provision of any supplementary foundation or base for carrying the load.

65 Having described my invention, I claim:

1. The combination with a wheel and a journal box, of a jack having means for engaging said wheel with either side of said jack adjacent to the wheel, a ram for engaging said box, mechanism for spreading said ram and means, and means preventing rotation of said ram during such spreading. 70

2. In apparatus of the character described, the combination of a stanchion, having a plurality of edges symmetrical with respect to a center line between them and with a recess between them, a ram, means for moving said ram relatively to said stanchion and means preventing rotation of said ram during such relative movement. 75

3. In apparatus of the character described, the combination with a casing, of a ram movable relatively to said casing, means comprising a plurality of superposed wedges in said casing for operating said ram, said casing holding said ram against movement in the direction of movement of said wedges, and means comprising a revoluble member for reciprocating said wedges, said revoluble member being journaled in said casing beyond the plane of said ram. 85

4. In apparatus of the character described, the combination with a casing, of a ram movable relatively to said casing transversely to the length thereof, means comprising a reciprocable wedge in said casing for operating said ram, said casing holding said ram against movement in the direction of movement of said wedge, anti-friction devices for supporting said wedge, the face of said wedge engaging said devices being normal to the line of movement of said ram, and revoluble means for reciprocating said wedge, said means being journaled in the casing beyond the zone of said ram. 105

5. In apparatus of the character described, the combination with a stanchion having a scalpriform edge and a ram, of a plurality of oppositely tapered superposed complementary wedges between said stanchion and ram, and means for moving said wedges in opposite directions. 110

6. In apparatus of the character described, the combination with a stanchion and a ram, of a plurality of oppositely tapered wedges between said stanchion and ram, means for effecting relative movement of said wedges, anti-friction devices between the surfaces of said wedges, anti-friction devices between said stanchion and one of said wedges, and anti-friction devices between said ram and the other of said wedges. 115

7. In apparatus of the character described, the combination with a stanchion and a ram, of a plurality of oppositely tapered wedges between said stanchion and ram, means for effecting relative movement of said wedges, revoluble anti-friction devices between said wedges, and means for maintaining said anti- 125

friction devices between said stanchion and ram.

8. In apparatus of the character described, the combination of a casing and a ram movable relatively thereto, a plurality of oppositely tapered wedges in said casing for operating said ram, means for effecting relative movement of said wedges, a cage having means connecting it with said casing, and rollers in 10 said cage between said wedges.

9. In apparatus of the character described, the combination of a casing containing an aperture, a ram movable in said aperture relatively to said casing, means comprising a 15 wedge and a rack projecting from the thicker end of said wedge for operating said ram, and a revoluble device engaging said rack for operating said wedge.

10. In apparatus of the character described, the combination with a casing, of a ram movable relatively to said casing, means comprising a wedge for operating said ram, a rack connected with said wedge and a pinion journalled in said casing beyond the zone of 25 said ram and engaging said rack.

11. In apparatus of the character described, the combination with a casing and a ram, of means comprising a plurality of oppositely tapered wedges for operating said 30 ram, racks connected respectively with the thick end and the thin end of the respective wedges, and a pinion journalled in said casing and disposed between and engaging said racks.

12. In apparatus of the character described, the combination of a casing, a stanchion connected therewith and having spaced edges, rollers journalled in said stanchion, a wedge reciprocable in said casing on said 40 rollers, a rack connected with said wedge, a cage connected with said casing, rollers in said cage and resting on the inclined surface of said wedge, a second wedge having an inclined surface engaging said rollers last 45 named, a rack connected with said wedge second named, rollers engaging said wedge last named, a ram carried by said rollers, a pinion journalled in said casing and engaging said racks, and a gear train for operating 50 said pinion.

13. In a device of the character described, an elongated hollow casing, a stanchion projecting from the casing toward one end thereof of having terminal edges symmetrical relative to the center line of the stanchion and spaced by a recess, said edges lying in planes substantially parallel with the adjacent side faces of the casing, a ram slidably mounted in the casing and disposed within the planes 55 of said edges, means in the casing for effecting relative movements of the ram and casing, including actuating elements disposed at the other end of the casing, the terminal edges of the stanchion and the sides of the casing 60 being substantially symmetrical relative the

longitudinal axis of the casing so that the jack may be used with either side of the casing in juxtaposition to the work.

14. In a device of the character described, an elongated hollow casing, a stanchion carried toward one end thereof, cooperating oppositely tapered wedge elements disposed in the casing above the stanchion, a ram vertically slidable in the casing in substantial alignment with the stanchion, means disposed in the casing toward the other end thereof for effecting relative movements of the wedge elements and including laterally projecting engaging devices; the casing, the stanchion, the ram, and the engaging devices being substantially symmetrical so that the jack may be used with either side thereof in juxtaposition to the work.

15. A device of the character described comprising a casing, a ram slidable in the casing and arranged to engage the work, a stanchion mounted on the casing, means comprising a wedge in said casing for moving the ram relative the casing and for imparting the thrust on the ram to the stanchion substantially in the center thereof, and terminal edges on the stanchion spaced by a recess and disposed laterally on each side of the center line thereof, each edge arranged to engage a fulcrum and impart the thrust of the ram thereto, whereby the jack may operate without undue contact of the side of the casing against the adjacent work.

16. In a journal jack, a hollow casing, a ram slidably mounted toward one end thereof, a stanchion carried by the casing in substantial alignment with the ram, a plurality of oppositely tapered superposed wedge elements mounted in the casing between the ram and the stanchion, and means toward the opposite end of the casing for actuating the wedge elements in opposite directions to effect relative movement of the ram and casing.

17. The combination with a casing, a ram slidably mounted therein, oppositely tapered superposed wedge elements disposed in the casing in alignment with the ram, a slot formed in the wall of the casing, a cage carrying rollers disposed between the meeting faces of the wedge elements, a pin anchoring the cage against longitudinal movement in the casing by engagement with the slot, and means disposed toward the opposite end of the casing for actuating said wedge elements.

In testimony whereof I have hereunto set 120 my name this 12th day of March, 1925.

H. J. SMITH.
